UNITED STATES PATENT OFFICE.

SYLVANUS PERCIVAL VIVIAN, OF CHELSEA, LONDON, ENGLAND.

MACHINE FOR ARRANGING PAPERS, CARDS, AND LIKE ARTICLES.

Application filed January 3, 1923. Serial No. 610,536.

To all whom it may concern:

Be it known that I, SYLVANUS PERCIVAL VIVIAN, a subject of the King of England, residing at 22 Royal Avenue, Chelsea, London, S.W.3, England, whose post-office address is 22 Royal Avenue, Chelsea, London, S.W.3, England, have invented a certain new and useful Machine for Arranging Papers, Cards, and Like Articles, of which the following is a specification.

This invention consists of a machine which, on being fed with a pack or number of card index slips, dockets or other cards or papers, or of the like articles of a suitable size, will mechanically arrange them so as to exhibit the end margins of every slip or like article in a continuous parallel series.

The practical application and utility of such a machine is best indicated by a few examples. It will, for instance, bridge the gulf between the "card index" method by which each of a series of entries is borne upon a separate card or paper, and the schedule or list method by which the consecutive entries are shown as a continuous series on a single document. Each method had its advantages and disadvantages.

The "card index" method has the advantages that the order of the entries can be altered, and that new entries can be inserted and obsolete entries removed; but it has many disadvantages due to the fact that the consecutive entries cannot be scanned, examined or compared as a single visible series. The schedule or list method has the disadvantages that it is practically impossible to change the order of the entries or to insert new ones. But the continuous series can be taken in by the eye; entries sought can be easily found and the correctness of the order speedily verified. If the entries are figures, they can be added by sight, while the tabular arrangement of any matter, impossible in a card index, is a natural feature of the schedule or list.

The present invention enables the advantages of both methods (hitherto mutually exclusive) to be simultaneously realized. The entries may be kept in card index form, i. e., on separate cords or slips; but the matter of the entries or selected portion of it, if borne upon the end margins of the slips can be shown in the form of a continuous schedule when the pack is put through the machine.

In other respects, moreover, the machine

appears likely to serve a useful purpose. For example, in many commercial or clerical operations it is necessary to assemble a number of forms or dockets collected from different quarters and to compute the figures upon them. They cannot be so computed by sight, while if a calculating machine is used the pace is slowed down by the operator having to turn each docket over in succession. The machine which forms the subject of this invention will arrange such dockets in a long column, or ribbon, with the margin of each exposed, thus exhibiting in tabular form any figures entered upon the margins; in this form they can be computed by sight, while if a calculating machine is used the operator can work as though from a tabular list of figures.

I believe that devices have already been patented for displaying in a continuous series the entries which are borne upon separate slips or cards. These devices, however, so far as I am aware, differ fundamentally from the present invention in respect that they all consist of some form of container in which the cards are arranged by hand and in which they are kept so displayed.

My invention is illustrated in the accompanying drawings, wherein—

Fig. 1 is a side elevation of the machine constructed according to my invention.

Fig. 2 is a plan view of the same, the carrier bands being omitted;

Fig. 3 is a diagrammatic view of the carrier bands, a pack of cards being shown in initial position on the front band and a pack of fanned-out cards on the upper band.

Fig. 4 is an enlarged diagrammatic view showing the relations of the cards in their forward passage between the drums.

Fig. 5 is a similar view showing the relations of the cards in their rearward or succeeding passage between the drums.

Fig. 6 is a similar view of a modification of the arrangement shewn in Fig. 3.

The same letters of reference are used for the same or corresponding parts in all the figures of the drawings.

Referring first to Figs. 1 to 3—

The machine is constructed substantially as follows: Two drums, A and B, each mounted on a spindle, are arranged with their axes parallel. One drum B rotates in fixed bearings in a standard C secured to the base D of the machine and the other

drum A rotates in bearings in a frame D' pivoted at D² to a standard D³ on the base D⁴ below the spindle A' of the drum A, so that said drum A, its spindle A' and the frame D' can swing to and fro on a line at right angles to the axes of the drums. The drum A rests normally with its circumference in contact with the circumference of the drum B.

10 In front and in rear of the two drums respectively extend two galleries or channels E and F supported by standards C' C² C³, &c., on the base D⁴ and consisting preferably of two longitudinal bars or flat strips of wood or metal united by transverse bars E', F'. At the extremity of each channel remotest from the drums a pair of rollers, E², E³ and F², F³ is mounted, consisting of a driven roller and a friction roller. The driven roller in each pair (E² or F²) is mounted on a spindle, E⁴, F⁴, rotating in fixed bearings forming part of the sides of the channel E or F. A grooved pulley (E⁵, F⁵) is fixed upon the spindle (E⁴, F⁴) 25 in order that the roller E² or F² may be made to rotate by means of a belt (G, H) driven from a central driving wheel I. The friction roller (E³, F³) rotates in bearings in a frame (E⁶, F⁶) pivoted to the sides of the channel E or F. Each friction roller is held in contact with its driven roller by means of springs J, the object being to cause the driven rollers to grip endless carrier bands K, K', which are passed between them 30 and their friction rollers, so that the said carrier bands can be made to travel by the rotation of the driven rollers E², F², when driven off the central driving wheel I.

In the rear gallery or channel F near to 40 the rear drum B two small guide rollers L, L' are mounted on spindles capable of rotating freely in fixed bearings in the sides of the channel F. Below the driven roller at the end of the rear channel F is mounted 45 an additional guide roller L² with a spindle rotating in bearings in a frame L³ pivoted on the sides of the channel F and drawn towards the rear by springs L⁴ secured to the end of the channel F.

50 The central driving wheel I is hand or power operated with two peripheral grooves of equal driving speed. It is fitted with the two driving belts G, H passing over the pulleys E⁵, F⁵ on the driven rollers; the belt G passing over the pulley of the front driven roller E² is crossed so that the motion of the central driving wheel rotates the driven rollers E², F² in opposite directions.

55 The machine is provided with a third end- 50 less band K² which serves as an extension of the band K. All three bands are preferably of the same breadth as the drums and rollers over which they pass, and there is a little slack in each of them.

55 The band K' passes round the front drum

A and the rear driven roller F²; the band K passes round the front driven roller E², the rear drum B and the small guide roller L. The extension band K² passes round the small guide roller L', the additional guide 70 roller L² and the rear friction roller F³.

The machine is operated as follows:—A pack of paper, card or other slips, indicated generally at P, is placed horizontally upon the front band K between the sides of the channel E with the lateral edge of the said pack in contact with or otherwise parallel to one of the said channel sides. The central driving wheel I is then rotated counter-clockwise; and owing to the consequent 75 travel of the band the pack moves towards the front drum A, passes between the upper and lower bands K and K' under the front drum A, thence between the two drums and over the rear drum B. The rotation of the central driving wheel is then reversed, when the slips make the reverse journey, and the to-and-fro movement is continued by the reciprocatory rotary movement of the central driving wheel.

This movement of the pack under and over the drums bends the slips alternately concave and convex. The carrier band outside the pack on the drum farthest in the direction of travel is tight (it being directly 95 pulled by the relative driven roller); while the band outside the pack on the other drum is loose. The alternate flexing and reflexing of the pack, in combination with the gripping of the said pack by the pressure upon the relative drum of the one band or the other (according to the direction of travel) results in the pack beginning to "fan out" 100 and the margins to overlap. As the length of the "fanned out" pack increases, the distance of the travel to and fro is increased by prolonging the movements of the central driving wheel; and the motion is continued until the pack is sufficiently "fanned out" 105 and the desired extent of each margin 110 is exposed.

The front upper edge of the pack will be exhibited to sight in a continuous series when the slips travel forward into the front channel. The "fanning out" will, of course, also expose the rear under margins of the pack, though they will be below and out of sight. If, however, the central driving wheel is rotated counter-clockwise sufficiently far, the whole ribbon of slips will be carried on to the extension band K², thence round the outside of the rear driven roller F² and under the rear friction roller F³ on to the top of the rear channel F, along which it will travel 115 forward with the under margins uppermost 120 and exposed to view.

Obviously, a series of pairs of drums for alternately concavely and convexly bending the slips in the pack may be arranged in the machine if so desired.

The modification shown in Fig. 6 is intended for limp materials such as thin paper, whereas the other form is adapted for flexing stiffer material such as cards.

5 In this modification the band K passes round the drum B, then back under and over the drum A round the guide roller L, back to driven roller E²; and the band K' passes from driven roller F² over and under the drum A between the drums A and B over and under the drum B and back over the drum A to driven roller F².

Additional spring pressed guide rollers may be inserted where required.

15 Instead of the carrier bands being moved by simultaneous drive, each of the two driven rollers E² and F² may be arranged to run free in one direction and not in the other according to the direction of travel of the bands.

I claim:—

1. A machine for fanning out papers, cards, and the like articles, to exhibit the end margins of every such article in a continuous series, including means for subjecting the articles to a traveling movement, means cooperating with said first mentioned means to flex and reflex said articles during travel, and means for applying pressure to alternate sides of the articles during their flexing and reflexing.

2. A machine for fanning out papers, cards and the like articles so as to exhibit the end margins of every such article in a continuous series, comprising means for flexing and reflexing said articles while under alternately applied pressure, said means comprising adjacent rotating drums, and endless bands cooperating with said drums for receiving the articles between them.

3. A machine for fanning out papers, cards, and the like articles, so as to exhibit the end margins of every such article in a continuous series, comprising means for flexing and reflexing said articles while under alternately applied pressure, said means comprising adjacent rotating drums and endless carrier bands passing over said drums and between which the articles are arranged.

4. A machine for fanning out papers, cards and the like articles, comprising a frame, a drum rotating in fixed bearings in said frame, a second drum mounted in a bearing pivoted to a standard on said frame so that said second drum normally rests in surface contact with the first drum, rollers mounted in bearings on said frame, endless carrier bands passed around said drums and rollers and means for driving said rollers to rotate the drums in opposite directions.

5. A machine for fanning out papers, cards and the like articles, comprising a frame, a drum rotating in fixed bearings in

said frame, a second drum mounted in a bearing pivoted to a standard on said frame so that said second drum normally rests in surface contact with the first drum, rollers mounted in bearings on said frame, endless carrier bands passed around said drums and rollers, means for driving said rollers to rotate the drums in opposite directions comprising a driving wheel mounted in bearings on the frame, driven wheels mounted in bearings on the frame, and endless belts connecting said driving and driven wheels.

6. A machine for fanning out papers, cards and the like articles, comprising a frame, a drum rotating in fixed bearings in said frame, a second drum mounted in a bearing pivoted to a standard on said frame so that said second drum normally rests in surface contact with the first drum, rollers mounted in bearings on said frame, endless carrier bands passed around said drums and rollers, means for driving said rollers to rotate the drums in opposite directions comprising a driving wheel mounted in bearings on the frame, driven wheels mounted in bearings on the frame, endless belts connecting said driving and driven wheels, and anti-friction rollers bearing against the driven wheels and mounted in pivoted frames connected by springs to the machine frame.

7. A machine for fanning out papers, cards and the like articles, comprising a frame, a drum rotating in fixed bearings in said frame, a second drum mounted in a bearing pivoted to a standard on said frame so that said second drum normally rests in surface contact with the first drum, rollers mounted in bearings on said frame, endless carrier bands passed around said drums and rollers, means for driving said rollers to rotate the drums in opposite directions comprising a driving wheel mounted in bearings on the frame driven wheels, endless belts connecting said driving and driven wheels, anti-friction rollers bearing against the driven wheels and mounted in pivoted frames connected by springs to the machine frame, and a tension roller mounted in a pivoted frame connected by springs to the machine frame.

8. A machine for fanning out papers, cards and the like articles, comprising a frame, a drum rotating in fixed bearings in said frame, a second drum mounted in a bearing pivoted to a standard on said frame so that said second drum normally rests in surface contact with the first drum, rollers mounted in bearings on said frame, endless carrier bands passed around said drums and rollers, means for driving said rollers to rotate the drums in opposite directions comprising a driving wheel mounted in bearings on the frame driven wheels, endless belts connecting said driving and driven wheels, anti-friction rollers bearing against the

driven wheels and mounted in pivoted frames connected by springs to the machine frame, a tension roller mounted in a pivoted frame connected by springs to the machine frame, and galleries or channel ways supported by standards on the base of the machine frame to act as guide ways for the articles fed to and from the rotating drums.

In testimony whereof I have hereunto set my hand in presence of two subscribing witnesses this 15th day of December, 1922. 10

SYLVANUS PERCIVAL VIVIAN.
